UNITED STATES PATENT OFFICE

2,600,909

CABINET FOR AMUSEMENT APPARATUS

Nels A. Nelson, Chicago, Ill., assignor to
Raymond T. Moloney, Chicago, Ill.

Application September 17, 1945, Serial No. 616,669

3 Claims. (Cl. 312—107)

1

This invention has for its principal object the provision of improvements in cabinet structures, particularly those employed in conjunction with game and amusement apparatus to house various mechanisms and playing instrumentalities, the improvements relating more specifically to the provision of a cabinet structure having separable unit-sections to facilitate servicing, change or replacement of game features or scoring features, and transport.

It is a further object of the invention to provide a novel cabinet construction consisting of a score and control cabinet, as one unit, and a game cabinet, as another unit and shaped for attachment to the first cabinet or unit so that the two units together form the game, either unit being replaceable by another to alter the playing or scoring features, or by identical units for quick servicing in event of mechanical or electrical failure of any of the instrumentalities comprising the game means.

Additional objects and aspects of novelty relate to the construction of the cabinet sections in a manner facilitating handling and shipping thereof; to the construction of the cabinet sections in a manner such that they will present an artistic game unit in assembled condition; to the provision of novel means for mounting various mechanisms employed in such games whereby to facilitate servicing, installation, electrical connections, etc., all of which will appear more fully as the following description proceeds in view of the accompanying drawings in which:

Fig. 1 is a perspective view of the assembled game;

Fig. 2 is a perspective view of one of the cabinet sections or game units;

Fig. 3 is a perspective view of another one of the cabinet or game units;

Fig. 4 is a rear elevation of the cabinet section shown in Fig. 3;

Fig. 5 is a rear perspective fragment of the cabinet section shown in Fig. 4 and showing particularly the novel apparatus mounting means;

Fig. 6 is a fragmentary, front, elevational view of the cabinet section shown in Fig. 2;

Figs. 7 and 7a show details of the retractable leg structure.

Referring to Fig. 1, the assembled game structure includes a front game section generally indicated at 10 and shown separately, that is, disassembled, in Fig. 2, and a rear scoring panel section 11, shown separately in Fig. 3, these two sections being joined together along the line 12, Fig. 1.

The front section 10 consists of an upright pedestal portion 13 having an integral horizontal case section 14, the latter having a glass top 15,

2

beneath which one or another arrangement of playing or game instrumentalities are arranged, as in a ball-rolling game, of which there are many varieties well-known in the art.

5 Assuming the game of Fig. 1 to be a ball-rolling game, a ball propelling plunger 16 is provided at the front of the pedestal for launching balls, elevated to propelling position by an elevator plunger 17, these latter instrumentalities being well-known in the art and not described further herein since they do not per se constitute part of the invention.

The type of game chosen for illustration is of the coin-controlled variety, and accordingly there 15 is provided the usual coin depository 18, from which deposited coins pass into a known type of coin testing chute 19, mounted, as in Fig. 6, on the rear of a pedestal door 20, along with associated mechanisms customarily employed in such games.

20 Of importance to the invention is the fact that the ball-rolling or other game instrumentalities lodged beneath the glass top 15 may be of great variety and subject to frequent change or replacement in order that player-interest in the games may be constantly stimulated, and to the end of facilitating such replacement, the front or pedestal section 10 is detachable from the other section 11, bolt means 22, Fig. 2, being engageable in holes 23, Fig. 3, of the score panel section 11 to secure the two sections in assembled relation, as in Fig. 1. Thus, in order to replace the front section 10, it is not necessary to transport the entire game structure, but only the section being replaced.

25 In order that the front separable section 10 may be supported in normal upright position, when separated as aforesaid, there is provided a vertically shiftable leg 25 which may be held in any desired position of elevation by means of bolts 26 (Fig. 7) through the rear face plate 27 of the front section, engaging in vertical slots 28 (Fig. 8) in the leg, said bolts engaging nuts to hold the leg in adjusted position.

30 Thus, when the front section 10 is disengaged from the rear section 11, leg 25 is lowered and secured with its lower end resting on the floor level, as in Fig. 2; and when the front section 10 is assembled with the rear section, as in Fig. 1, leg 25 is raised clear of the floor and so secured, it being pointed out that this leg is positioned to fit flush against the rear section, particularly the lower panel part 11a thereof, Fig. 1, and in a median portion thereof so as to form a design element therewith to conceal artistically the nature of the leg element, when the latter is not in use to support the front section.

35 Where it is desired or necessary, as in case of

mechanical failure, to replace the rear section, the same considerations apply.

The rear section 11 for purposes of description and reference, is called the score cabinet, and includes a glass panel 30, Figs. 1 and 3, behind which various scoring indicia (not seen) appear when illuminated by small electric lamps 31, Fig. 5, responsive to playing of the game; and a further feature of the game cabinet construction resides in mounting lamps 31 on a panel 32, hinged to the rear cabinet section as at 33, Fig. 4, so as to be free to swing outwardly into the position of Fig. 5 for servicing, when latch means 34 is released, the panel 32 having in addition a shelf section 35 adapted to mount instrumentalities, such as a transformer 36, associated with the lamp score means 31.

As in Figs. 4 and 5, additional swinging panel means 40, provided with a shelf portion 41 supporting game instrumentalities 42, and upper panel means 45 having a shelf and shield portion 46, supporting instrumentalities 47 and 48, are respectively hinged to the cabinet by hinge means 49 and 50. Thus, game and score mechanisms for the rear score cabinet section 11 are housed therein on swinging members corresponding respectively to the several control units involved, so that each said unit may be serviced and wired or connected in manufacture with relative ease and accessibility by swinging the corresponding panel and shelf portions as needed.

It is well known in the art that games of the class to which the instant invention is adapted employ various electrical devices, for example ball-operated switches, on the playing field situated beneath the glass top 15, and the present cabinet construction provides for electrical connection with these devices by means of connecting cables 60 therefrom passing through openings 61 in the rear panel portion 27 of the front section or unit, said cables being passed through similar openings 62 cut in the score cabinet section (Figs. 2, 3 and 5) for connection with the electrical instrumentalities 42, 47, 48, etc.

Means for stabilizing the swinging shelf members 35, 41, 46, includes channel shaped brackets 49 (Fig. 4) mounted on a vertical side wall portion interiorly of the score cabinet to receive the edge portions of said shelves supportingly when the latter are swung into place.

It will now appear that the invention provides a form of knock-down cabinet construction peculiarly adapted to game apparatus of the class described, whereby the handling, shipping, replacement, servicing, and manufacture of such games is greatly facilitated; and it will appear further that the novel apparatus mountings on swinging shelf sections comprising separate units, e. g. 35, 40, 46 additionally facilitates manufacture and servicing.

I claim as my invention:

1. An apparatus cabinet comprising a first upright cabinet section having an access closure in a rear side thereof, a horizontal section projecting at approximately right angles from the forward side of said first section at a level between the upper and lower extremities of said first section and removably attached to the latter, said horizontal section terminating at its end remote from said first section in the rearward side of a second upright cabinet section pendently at right angles to said horizontal section, said second cabinet section having an access closure in a front side thereof, and leg means adjustable

up and down into position in the region of juncture of the horizontal section with the first section to support said horizontal section, cooperably with said second section, when the latter two sections are separated from the first section.

2. An apparatus cabinet comprising an upright rear cabinet having a base upon which said cabinet can stand alone, and a front pedestal having an integral horizontal cabinet section projecting approximately at right angles to the pedestal and having a terminus engageable with said rear cabinet at a level between the base and top thereof, means for securing said terminus to said rear cabinet, and a leg fitting up into said horizontal section inwardly of said terminus to fit close to said rear cabinet when the terminus is joined thereto, so that said leg appears as a design element of said cabinet, means mounting said leg for vertical movement into and out of position to support said terminus and thereby support said horizontal section cooperably with said pedestal when the leg is lowered, and means for securing said leg in raised or lowered condition.

3. A knock-down cabinet structure especially for housing apparatus and comprising an upstanding rear cabinet section, an upstanding front cabinet section of lesser height than the rear section and constituting a pedestal, a horizontally-extensive table section joined at one longitudinal end region to said pedestal such that the latter forms a support for said one end region, the opposite end region being removably joined to said rear cabinet for support by the latter, said opposite end region of the table section having at least one decorative and functional stand-by leg and means mounting the same thereon to move vertically from an extended table-supporting contact with a floor to a retractive position clearing the floor, said stand-by leg being situated in close proximity to the juncture of said opposite end region of the table with said rear cabinet so as to fit decoratively close to the latter to afford a predetermined decorative design in either extended or retracted condition when the table is assembled therewith as aforesaid, said leg-mounting means including means for releasably securing the stand-by leg in said retracted and extended conditions, said front and rear cabinet sections and said table section respectively including communicating chambered portions for receipt of cooperative apparatus.

NELS A. NELSON.
